UNITED STATES PATENT OFFICE.

JOHN KELLY, OF CHICAGO, ILLINOIS.

INTERNAL-COMBUSTION ENGINE.

1,360,536.

Specification of Letters Patent. Patented Nov. 30, 1920.

Application filed November 24, 1919. Serial No. 340,152.

To all whom it may concern:

Be it known that I, JOHN KELLY, a citizen of the United States, residing at 5958 Washington Boulevard, Chicago, in the county of Cook and State of Illinois, have invented a new and useful Improvement in Internal-Combustion Engines, of which the following is a specification.

My invention relates more particularly to internal combustion engines of the type employing electrically controlled valves for controlling the inlet to the cylinders, of the explosive charges to be fired for driving the engine, and the exhaust therefrom of the burnt gases; and my primary object, generally stated, is to so improve upon engines of this type that they will operate the better to perform the functions for which they are provided, and more particularly operate smoothly and evenly and with the minimum amount of noise; and furthermore to provide for an increased braking action, under the control of the operator, by the resisting action of the engine, as for example in descending relatively steep hills.

Referring to the accompanying drawing, the same shows, by a view in longitudinal sectional elevation, the upper portion of an internal combustion engine equipped with my improvements, this view being in a sense diagrammatic and showing, in a diagrammatic way, the circuits for operating the electrical elements controlling the valve, with a timer therefor interposed in these circuits.

In the particular construction shown, 1 represents a cylinder of an internal combustion engine water-jacketed at 2, and in which the piston represented at 3, and connected with the connecting rod 4, in accordance with common practice, operates. The upper end of the cylinder 1 contains a transversely extending, preferably cylindrical, bore 5 shown as extending entirely across the cylinder, with cap plates 6 and 7 apertured at 8 and 9, respectively, secured to extend across the ends of the bore. The upper end of the cylinder containing the bore 5 forms in effect a valve casing, preferably waterjacketed as indicated at 10, for a valve device controlling the inlet to the cylinder 1, of explosive charges to be fired, and the exhaust from the cylinder, of the burnt gases. The valve casing referred to, to the end above stated, contains in the wall thereof interposed between it and the cylinder 1, a port 11, and in its

opposite wall the ports 12 and 13 located at opposite sides of the opening 11 and preferably equi-distantly therefrom. The valve device referred to is formed of a rod section 14 extending through the bore 5 and equipped with heads 15 and 16 which have sliding fit in the bore 5, these heads being arranged at opposite sides of the port 11 and positioned relative to the ports 12 and 13, as hereinafter described. The ends of the rods 14 extend guidingly through the openings 8 and 9, and co-operating with the valve structure thus provided, are coiled springs 17 and 18 which surround the rod 14 and are confined, respectively between the head 16 and the plate 6, and between the head 15 and the plate 7, these springs, in the normal condition of the valve device being under compression. In this position of the valve device, the heads 15 and 16 extend into a position, as shown, wherein the ports 12 and 13 are out of communication with the port 11.

The opposite ends of the rod 14 form the cores of solenoid devices represented at 19 and 20, the coil of the solenoid 19 being represented at 21 and surrounding a space 22 into which the enlarged core-forming end 23 of the rod 14 extends to be movable lengthwise therein, and the coil of the solenoid 20 represented at 24 and surrounding the space into which the core-forming end 25 of the rod 14 extends and is longitudinally movable, whereby upon alternately energizing these solenoids the rod 14 with the heads 15 and 16 thereon is shifted first in one direction and then in the opposite direction. The shifting of the rod 14 to the left in the drawing, from the normal position represented therein, and against the action of the spring 18, by the energizing of the solenoid 20, operates to cause the port 12, which, in accordance with the illustrated embodiment of the invention would be in communication with a supply of explosive fuel, as for example a carburetor, to communicate with the interior of the bore 5 and the port 11, the port 13 being closed by the head 16. In the movement of the rod 14 in the opposite direction, and against the resistance of the spring 17, by the energizing of the solenoid 19, the head 15 is moved with the rod 14 to a position in which the port 12 is closed and the head 16 is moved with this rod to a position in which the port 13 is open to the interior of the bore 5 and to the port 11, the port 13

serving as the exhaust port of the engine. The operation of the valve mechanism as stated would be so timed relative to the reciprocations of the piston 3 and the ignition device (not shown) for the cylinder, that the port 12 will be in communication, through the bore 5, with the port 11, on the suction stroke of the engine, and the port 13 will be in communication, through the bore 5, with the port 11, on the exhaust stroke of the piston and preferably during the latter part of the explosion stroke. The timing of the valve device for the purpose stated, may be accomplished by any suitable mechanism, as for example by the timing apparatus represented at 26 and formed of a body member 27 supported, in any suitable manner. The member 27 carries contacts 31 and 32 which are out of electrical contact and which coöperate with a rotatable contact-making-and-breaking arm 33 mounted on a shaft 33^a adapted in its rotation to make contact successively with the said contacts on the member 27, the shaft 33^a being operated in timed relation to the crank-shaft of the engine, in any suitable manner, as from the shaft through the medium of which the ignition-timer is commonly actuated. One of the terminals of the coil 24 is grounded at 34 and its opposite terminal represented at 35 connects with the stationary contact 32. One of the terminals of the coil 21 is grounded at 36 and the other terminal thereof, represented at 37 connects with the stationary contact 31, the movable contact arm 33, being grounded as through the medium of a wire 38 containing a switch 39. The two circuits in which the solenoids 21 and 24 are respectively interposed, may be supplied with current from any suitable source. In the drawings the current is shown as supplied from two batteries 40 and 41 interposed, respectively, in these two circuits and operating to energize the solenoids respectively, as the contact 33 in its rotation progressively wipes against the stationary contacts of the member 27.

In the drawings the parts of the engine are shown in the positions they assume in the initial movement of the piston 3 on its explosion stroke. During the latter part of this stroke the contact-arm 33 engages the contact 31, thus energizing the solenoid 19 which operates to open the exhaust port 13 to the port 11 and closes the port 12, the exhaust remaining open during the remainder of the explosion stroke and during the exhaust stroke. At the end of the exhaust stroke the contact 33 leaves the contact 31 and engages the contact 32, thus energizing the solenoid 20 and deenergizing the solenoid 19, with the result of the valve shifting to a position in which the port 12 is open to the port 11 and the port 13 is

closed thereto, thus permitting the engine to suck an explosive charge into the cylinder on the suction stroke. Both solenoids are deenergized during the compression stroke and the major part of the explosion stroke so that both ports 12 and 13 are closed to port 11, during this operation of the engine.

It will be noted that when both of the solenoids are deenergized, the valve device occupies the position shown in the drawings wherein both ports 12 and 13 are closed to the port 11, this feature of construction being of special importance when the car equipped with the engine is descending a steep hill, as thereby, assuming the switch 39 to have been opened and remain open, each upward stroke of the piston 3 is in opposition to the resistance to compression of the fluid in the cylinder, thus presenting a relatively heavy drag and consequently braking action on the wheels of the car.

By the arrangement shown it will be noted, the valve device is balanced by the pressure and thus a slight amount only of power is required to operate the valve-device.

While I have illustrated and described a particular construction embodying my invention I do not wish to be understood as intending to limit it thereto as the same may be variously modified and altered without departing from the spirit of my invention.

What I claim as new and desire to secure by Letters Patent is:

1. In an internal combustion engine, the combination with its cylinder, of valve mechanism therefor controlling the inlet to, and the exhaust from, said cylinder comprising a valve device, spring means operating to normally hold said valve device in a position in which said cylinder is out of communication with the supply of fuel and the exhaust passage, and electrically-operated means operating to reciprocate said valve device alternately in opposite directions in opposition to said spring means.

2. In an internal combustion engine, the combination with its cylinder, of valve mechanism therefor controlling the inlet to, and exhaust from, said cylinder, comprising a longitudinally movable valve, spring means operating to normally hold said valve in a position in which said cylinder is out of communication with the supply of fuel and the exhaust passage, and electrically-operated means operating to reciprocate said valve alternately in opposite directions in opposition to said spring means.

3. In an internal combustion engine, the combination with its cylinder, of valve mechanism therefor controlling the inlet to, and the exhaust from, said cylinder, comprising a longitudinally movable valve,

- spring means operating to normally hold said valve in a position in which said cylinder is out of communication with the supply of fuel and the exhaust passage, solenoids 5 coöperating, respectively, with the opposite ends of said valve for reciprocating the latter alternately in opposite directions in opposition to said spring means, and means for alternately energizing said solenoids.
- 10 4. In an internal combustion engine, the combination with its cylinder containing a port, of valve mechanism therefor, controlling the inlet to, and the exhaust from, said cylinder, comprising a valve-casing, containing inlet and exhaust ports, a valve longitudinally movable in said casing operating when in one position to close both of said ports in the valve casing to said port in the cylinder, when in another position to 15 open said inlet port to said cylinder port and close said exhaust port to the latter, and when in still another position open said exhaust port to said cylinder and close said inlet port to the latter, and springs coöperating with said valve and operating to normally hold the latter in a position in which said cylinder port is out of communication with said inlet and exhaust ports, solenoid devices coöperating with the ends of said 20 valve and operating when alternately energized to reciprocate said valve, and means for alternately energizing said solenoids.
- 25 5. In an internal combustion engine, the combination with its cylinder containing a port opening into the interior thereof, of valve mechanism therefor controlling the inlet to, and the exhaust from, said cylinder comprising a casing containing inlet and exhaust ports, a rod longitudinally movable 30 in said casing and provided with heads adapted, in the reciprocations of said rod to alternately open and close said inlet and exhaust ports to said cylinder-port, and when said rod occupies a certain position, closing both said inlet and exhaust port to said cylinder-port, and coiled springs surrounding said rod and operating to maintain said valve in a position in which said inlet and exhaust ports are closed to said cylinder-port and yieldingly resisting lengthwise 35 movement of said valve, solenoids located adjacent the ends of said rod, the ends of the latter forming cores for said solenoids, said solenoids operating when alternately energized to alternately shift said rod in opposite directions, and means for alternately energizing said solenoids.
- 40 6. In an internal combustion engine, the combination with its cylinder containing a port, of valve mechanism therefor, controlling the inlet to, and the exhaust from, said cylinder, comprising a valve casing containing inlet and exhaust ports, a valve longitudinally movable in said casing and formed with two heads placed apart, said 45 valve operating when in one position to close at its heads both of said ports in the valve casing to said port in the cylinder, when in another position to open said inlet port to said cylinder port and close said exhaust to the latter and when in still another position open said exhaust port to said cylinder and close said inlet port to the latter, springs coöperating with said valve and operating to normally hold the latter in a position in which said cylinder port is out of communication with said inlet and exhaust ports, and electrically operated means operating to reciprocate said valve alternately 50 in opposite directions in opposition to said 55 spring means.

JOHN KELLY.
